UNITED STATES PATENT OFFICE.

OSCAR C. KAVLE, OF SYRACUSE, NEW YORK, ASSIGNOR TO HARVEY A. MOYER AND EMMIT G. LATTA, OF SYRACUSE, NEW YORK.

LINE-SPACING MECHANISM FOR TYPE-WRITING MACHINES.

No. 926,572.

Specification of Letters Patent.

Patented June 29, 1909.

Application filed April 14, 1906. Serial No. 311,757.

To all whom it may concern:

Be it known that I, OSCAR C. KAVLE, a citizen of the United States, residing at Syracuse, in the county of Onondaga and State of New York, have invented a new and useful Improvement in Line-Spacing Mechanisms for Type-Writing Machines, of which the following is a specification.

This invention relates to line spacing mechanisms, or platen rotating means for typewriting machines, and the principal object of the invention is to produce a desirable and efficient mechanism for the purpose of compact, simple and light construction.

More specific objects of the invention are to so construct and arrange those parts of the mechanism which are located between the platen and the platen carriage that they will permit the use of wide paper or sheets on the platen which project beyond the ends of the platen without interfering in any way with the sheets in the operation of the machine, so that wide sheets can be printed on a shorter and lighter carriage than is usually necessary; to arrange and construct the mechanism so as to enable the ready removal of the platen from the carriage; to provide simple and desirable means for adjusting the mechanism to produce single, double or triple line spaces by equal movements of the line space lever; to render the line spacing mechanism noiseless in action and to prevent the overrunning of the platen; and to provide a desirable friction brake which, when brought into play, throws the platen holding detent out of action, and serves to hold the platen in any position to which it is turned.

Other objects of the invention are to improve the platen rotating means of typewriting machines in the respects hereinafter pointed out and set forth in the claims.

In the accompanying drawings, consisting of two sheets: Figure 1 is an end elevation of a typewriter carriage provided with line spacing mechanism embodying the invention. Fig. 2 is a perspective view of one end of the platen and parts of the line spacing mechanism. Fig. 3 is a sectional elevation of the same parts in line 3--3, Fig. 1, looking toward the front of the machine. Fig. 4 is a plan view of the carriage with the central portion broken away. Figs. 5 and 6 are end sectional elevations of the platen showing the friction brake released and applied, respectively. Fig. 7 is an end sectional elevation

of the platen and line space mechanism in line 7--7, Fig. 4. Fig. 8 is a rear elevation, partly in section, on an enlarged scale, of one end of the platen and line space mechanism.

Like letters of reference refer to like parts in the several figures.

A, Figs. 1 and 4, represents the carriage of a typewriting machine, B the rotatable platen journaled thereon, and C the carriage shift frame or other support on which the carriage travels laterally of the machine to produce the letter spacing. The carriage shown consists of vertical end plates *a* *a'* rigidly connected at the lower portions by a body frame or casting *a*² and a front or scale bar *a*³, and moves on horizontal guides or ways *a*⁴ between its body frame and the support C. The carriage and shift frame or support C are preferably, though not necessarily, constructed as fully described in my application for patent, Serial No. 311,758, filed April 14, 1906.

The platen B, which may be of any usual or suitable construction, is secured to a platen shaft *d* which is provided at its ends with the usual finger wheels *d'* for turning the platen, and is journaled in the carriage in such manner that the platen can be readily lifted off of the carriage. Preferably bearing sleeves E E' surround the shaft between the ends of the platen and the hubs of the finger wheels *d'*, and are provided with reduced segmental circular grooved or reduced portions *e* which rest in correspondingly shaped seats *e'* (shown by dotted lines in Fig. 1) in the carriage end plates. Slots *e*² extending from the bearing seats to the upper edges of the end plates enable the insertion of the bearing sleeves into and their removal from the seats, but these slots are narrower than the seats and when the bearings are in the position shown in the drawings, with the flat sides of their reduced portions horizontal or crosswise of the slots, they cannot be lifted out of their seats. They are removed by first turning them in the seats until the flat sides of the reduced portions are parallel with the edges of the slots *e*². The bearing sleeves are held

from turning to releasing position, preferably by spring arms *f* which are fixed to or formed on the outer ends of the bearing sleeves and are provided at their free ends with pins *f'*, Fig. 8, adapted to enter holes *f*², Figs. 1, 2 and 8, in the end plates of the

carriage, and have knobs f^3 for withdrawing the pins from their holes.

While the detachable bearing described is preferred, the platen could be removably journaled in the carriage in any other suitable manner.

G represents the line space device, or lever, for rotating the platen. This lever in the machine illustrated is located at the 10 left-hand end of the carriage and projects forwardly from an upright shaft h to which it is fixed. Said shaft is located outside of the carriage end plate, being journaled in suitable bearings h' on the end plate, and is 15 provided with a rigid arm h^2 which projects inwardly through a slot h^3 , Fig. 1, in the end plate a and is pivoted to a link i which is located between the end plate and adjacent end of the platen and is pivoted at one end, 20 which extends toward the platen shaft, to a pawl lever K. This pawl lever is also arranged between the end plate and platen, is pivoted at its lower end below the platen shaft on a suitable pivot stud k projecting 25 inwardly from the end plate, and extends upwardly nearly to the top of the platen, being preferably curved to pass in rear of the platen shaft. The pawl lever and line space lever are held in their normal position 30 and returned to such position after operation by a suitable spring. A spring k' is shown (see Figs. 2, 3 and 8) coiled about the boss on the end plate for the pawl lever pivot with one end hooked around the lever 35 and the other end entering a hole in the end plate a . A pawl L is pivoted to and extends forwardly from the upper end of the pawl lever and has a lateral projection or nose l , Figs. 2, 4 and 5, at its front end adapted to 40 engage with the teeth of a ratchet wheel l' secured to the platen. The ratchet wheel preferably consists of a plate screwed or otherwise fixed directly to the end of the platen. The front end of the pawl is pressed 45 downwardly toward the teeth of the ratchet wheel by a flat spring l^2 secured to the pawl lever and bearing at its free end against a pin l^3 on the upwardly and rearwardly projecting tail or rear end of the pawl, see Figs. 50 2 and 7. The nose of the pawl is normally held out of engagement with the ratchet teeth against the action of said spring l^2 by a pawl lifter M arranged beside the ratchet wheel and having a segmental circular edge 55 on which a depending projection at the front end of the pawl is adapted to ride in the movements of the pawl. When the pawl lever is moved rearwardly to turn the platen, the pawl is held off of the ratchet teeth until 60 its front end clears the rear edge of the pawl lifter and it is only the remainder of the movement of the pawl which is effective in turning the platen. By shifting the pawl lifter forwardly or rearwardly around the 65 axis of the ratchet wheel the effective

movement of the pawl can be lengthened or shortened to increase or decrease the amount of rotation of the ratchet wheel. Thus the platen can be turned for one, two or more line spaces by equal movements of 70 the line space lever and pawl lever by properly adjusting the pawl lever M.

The pawl lifter preferably consists of an arm or plate fixed to or formed on the inner end of the adjacent bearing sleeve E for the 75 platen shaft, and this bearing sleeve is made rotatably adjustable for shifting the pawl lifter. Therefore, the end plate a in which said bearing sleeve is seated is provided with a series of the holes f^2 into either of which the 80 pin f' on the spring arm at the outer end of the bearing sleeve can be engaged. By engaging the pin f' in the proper hole f^2 the pawl lifter is held in the proper position for producing single, double or triple line spaces. 85 The pawl lifter could be separate from the bearing sleeve and separately adjusted and produce the same results.

N represents a stop for limiting the movement of the pawl. The stop, see Figs. 2, 4-7, 90 preferably consists of a stud secured on the inner side of the carriage end plate a by a screw n passing through the end plate. The stud is located in the path of and is adapted to be engaged by the tail of the pawl L. 95 When the tail of the pawl strikes the stop, not only is the movement of the pawl, pawl lever and line space lever arrested, but the nose of the pawl is pressed forcibly down between two teeth of the ratchet wheel, and the 100 platen is thus effectually held from overrunning the movement of the pawl. As soon as the operator releases the line space lever, the pawl lever is returned by its spring k' and the pawl is thus moved away from the stop and 105 its front end rides up on the pawl lifter which holds the pawl off of the ratchet teeth, so that noise is avoided in the return movement of the pawl. The arm h^2 on the shaft of the 110 line space lever G is set at such an angle that it approaches nearly to the line of the link i when the pawl strikes the stop N, and the effect of the arrangement is to allow a rapid 115 movement of the pawl at the start or while passing over the pawl lifter, and to lessen its speed toward the end of its movement, thereby lessening the shock of stopping the pawl and increasing the leverage of the line space lever so as to more securely hold the ratchet wheel and platen from overrunning when the 120 pawl is arrested.

O, Figs. 2, 4-8, represents a pivoted detent carrying a small roller p at its free end which is pressed by a suitable spring p' against the teeth of the ratchet wheel for holding the 125 platen in the usual manner. Preferably the detent is pivoted on the stop stud N and a curved spring p' is employed having a wide upper end bent around the stud N with inbent edges fitting in slots in the opposite sides of 130

the stud to secure the spring thereon. The securing screw *n* for the stud *N* enables the stud to be rotatably adjusted to give the desired tension in the detent spring.

5 When it is desired to lift the platen off of the carriage, the pawl *L* is turned up to the position shown by broken lines in Fig. 1. When the pawl is swung up to this position the pin *l*, against which its spring *l* bears, 10 passes the center and the spring also serves to hold the pawl up until it is restored to the normal position by hand.

Q, Figs. 3, 5 and 6, represents a friction brake consisting of a ring loosely surrounding 15 the hub of the platen in a circular central opening *q* in the ratchet wheel. The outer edge of the brake ring and edge of the opening *q* are conical or beveled, as shown. An arm or lever *q'* rigid with the brake 20 ring extends rearwardly therefrom and is provided with a projection *q*² having a cam edge which bears against the projecting end of the roller pindle of the detent *O*. When the brake lever is raised to the 25 position shown in Fig. 6, the cam edge of the projection *q*² presses the detent roller out of contact with the teeth of the ratchet wheel and it is held in such position by the engagement of the roller pindle in a notch *q*³ in the 30 edge of the cam projection *q*². The pressure of the detent spring *p* on the brake lever, when the detent is thus held, acts to wedge the conical brake ring in the opening in the ratchet wheel, thereby creating sufficient friction 35 on the ratchet wheel to hold the platen against accidental rotation. When the brake is thus applied and the detent held away from the ratchet wheel the platen can be turned to any desired position, by the finger 40 wheels *d'*, and held there by the friction of the brake. The friction caused by the brake depends on the angle of its conical edge and the tension of the detent spring, which is adjustable, as before stated. The described 45 coöperation of the brake and detent is not necessarily restricted to the particular form of the brake shown.

It will be seen from Figs. 2 and 7 that the pawl lever and its operating link and arm on 50 the shaft of the line space lever are located at the end of the platen within a circular space of the diameter of the platen and that the brake lever, detent and tail of the pawl, which extend beyond the limits of such 55 space, project rearwardly and upwardly from the platen. The parts arranged in this way permit the use of wide sheets extending beyond the ends of the platen, for the sheets can pass in the usual forward direction under the brake lever and detent and up around the platen under the pawl lever and its operating link and arm, and rearwardly from the platen over the pawl, 60 brake lever and detent without interference 65 from any of said parts. Sheets as wide as

the distance between the carriage end plates can therefore be used, and the effect of this construction is to permit the carriage for a given width of paper to be made nearly one inch shorter than usual, with a consequent 70 reduction in weight and gain in compactness.

R, Fig. 1, represents a guard rail, one of which is arranged at each end of the carriage. These rails are curved, being attached at their ends to the front and rear edges of the carriage end plates, and have substantially horizontal portions located above the parts of the carriage operating mechanism located at the ends of the carriage to prevent the operator's hands from 75 striking these parts. The guard rails are not claimed herein, but are disclosed and claimed in said application for patent, Serial No. 311,758, filed Apr. 14, 1906.

I claim as my invention:

1. In a typewriting machine, the combination of a carriage, a rotatable platen supported by the carriage, a line space lever, and a pawl lever separately pivoted to the carriage, operative connections between said levers, a ratchet wheel connected to the platen, and a pawl for transmitting motion from said pawl lever to said ratchet wheel, said operative connection, pawl lever, and pawl being arranged substantially within a 90 circular space directly opposite the end of the platen and of like diameter therewith, whereby a sheet passing around the platen can project beyond the same around said parts, substantially as set forth. 100

2. In a typewriting machine, the combination of a carriage, a rotatable platen supported on the carriage, a line space lever mounted on the carriage, connections between the line space lever and the platen located between one end of the platen and the adjacent end of the carriage, and a brake lever and brake at the end of the platen, said parts being arranged within the space bounded by the projecting edge of a sheet on the 110 platen to permit the sheet to pass under the brake lever and around said connections without interference, substantially as set forth. 105

3. In a typewriting machine, the combination of a carriage, a rotatable platen supported on the carriage, a line space lever mounted on the carriage, connections between the line space lever and the platen located between one end of the platen and the 120 adjacent end of the carriage, and a line space adjusting device, said connections and adjusting device being arranged within the space bounded by the projecting edge of a sheet on the platen to permit the sheet to 125 pass under and around said parts without interference, substantially as set forth.

4. In a typewriting machine, the combination of a carriage, a rotatable platen supported on the carriage, a line space lever 130

- mounted on the carriage, and connections between the line space lever and the platen, a line space adjusting device, a platen detent, and a brake, all located between one end of 5 the carriage and the adjacent end of the platen and arranged within the space bounded by the projecting edge of a sheet on the platen to permit a sheet to pass under and around said parts without interference, substantially as set forth. 10
5. In a typewriting machine, the combination of a carriage, a platen journaled on the carriage, a line space lever on the carriage, a separate pawl lever arranged between one end of the carriage and the adjacent end of the platen and connected to said line-space lever, a pawl connected to said pawl lever for turning the platen, said pawl lever, pawl and the connection between said 15 line space and pawl levers being contained substantially within a circular space directly opposite to the end of the platen and of like diameter therewith, substantially as set forth. 20
- 25 6. In a typewriting machine, the combination of a carriage which moves laterally of the machine, a platen journaled on the carriage and moving therewith, a line space lever pivotally supported by the carriage to swing laterally of the machine, an upright pawl lever pivotally connected at its lower end to the carriage, and connections between the two levers and between the pawl lever and platen arranged within the space bounded by the projecting edge of a sheet passing around the platen, substantially as set forth. 30
7. In a typewriting machine, the combination of a carriage, a platen journaled on the carriage, a line space lever pivoted on the outside of the carriage, a pawl lever pivoted on the inside of the carriage, operative connections between the two levers and between the pawl lever and platen, said pawl lever and connections being arranged adjacent to the 40 end of the platen within the space bounded by the projecting edge of a sheet passing around the platen, substantially as set forth. 45
8. In a typewriting machine, the combination of a carriage, a platen journaled on the carriage, a forwardly-projecting line space lever having a vertical pivotal support, and a pawl lever having a horizontal pivotal support at its lower end, both lever pivots being supported by the carriage adjacent to 50 one end of the platen, and connections between the two levers and between the pawl lever and platen arranged substantially within the space bounded by the projecting edge of a sheet passing around the platen, substantially as set forth. 55
9. In a typewriting machine, the combination of a carriage, a platen journaled on the carriage, a toothed wheel secured to one end of the platen, a line space lever on the outside of the adjacent end of the carriage, 60 and a separate pawl lever arranged between said ends of the carriage and the platen and connected to said line space lever, a pawl on said pawl lever engaging said toothed wheel, said pawl lever, pawl and connection being arranged within the space bounded by the projecting edge of a sheet passing around the platen, substantially as set forth. 70
10. In a typewriting machine, the combination of a carriage, a platen journaled on the carriage, a toothed wheel secured to one end of said platen, a line space lever on the outside of the adjacent end of the carriage, a pawl lever pivoted on the inside of said end of the carriage below the axis of the platen and above the underside of the platen, a connection between said pawl lever and line space lever, and a pawl connected to the upper end of said pawl lever and engaging said toothed wheel, substantially as set forth. 75
11. In a typewriting machine, the combination of a carriage, a platen journaled on the carriage, a toothed wheel secured to one end of the platen, a line space lever on the outside of the adjacent end of the carriage, 80 an upright pawl lever pivoted on the inside of said end of the carriage below the axis of the platen, a connection between said pawl lever and said line space lever, and a pawl connected to the upper end of said pawl lever and engaging said toothed wheel, substantially as set forth. 85
12. In a typewriting machine, the combination of a carriage, a platen supported on the carriage, a toothed wheel secured to one end of the platen, a line space lever, an upright shaft to which said line space lever is connected and which is journaled on the outside of the adjacent end of the carriage, an upright pawl lever pivoted on the inside of said end of the carriage, an arm secured to said shaft, a link connecting said arm to said pawl lever, and a pawl secured to the upper end of said pawl lever and engaging said toothed wheel, substantially as set forth. 90
13. In a typewriting machine, the combination of a carriage, a platen journaled on the carriage, a toothed wheel secured to one end of the platen, a line space lever on the adjacent end of the carriage, a separate pawl lever arranged between said ends of the carriage and platen and connected to said line space lever, a pawl on said pawl lever engaging said toothed wheel, and a spring located inside of said end of the carriage for returning said levers to normal position after operation, substantially as set forth. 95
14. In a typewriting machine, the combination of a carriage, a platen journaled on the carriage, a toothed wheel connected to said platen inside of the end of the carriage, a line space lever on the carriage, a separate 100
- 110
- 115
- 120
- 125
- 130

pawl lever pivoted on the carriage between the same and said toothed wheel, a pawl on said pawl lever for actuating said toothed wheel, and a stop on the carriage to limit the movement of said pawl, substantially as set forth.

15. In a typewriting machine, the combination of a carriage, a platen having end journals removably supported on the carriage, a lever arranged between one end of the carriage and the adjacent end of the platen at one side of the platen journal, means for operating said lever connected thereto below said journal, and a device arranged over said journal and connected to said lever for turning the platen and being movable to allow the removal of the platen from the carriage, substantially as set forth.

16. In a typewriting machine, the combination of a carriage, a platen removably supported at its ends on the carriage, a toothed wheel connected to one end of the platen, an upright pawl lever adjacent to one end of the platen, means for actuating the same, a pawl at the upper end of said pawl lever for actuating said toothed wheel, said pawl being movable to permit the platen to be lifted out of the carriage, and means for holding the pawl in the position to which it is moved, substantially as set forth.

30 17. In a typewriting machine, the combination of a carriage, a platen, a shaft to which the platen is secured and which is removably supported in the ends of the carriage, a toothed wheel secured to one end of the platen, an upright pawl lever adjacent to said toothed wheel, means for actuating said pawl lever, a pawl on said lever overhanging the platen shaft for actuating said toothed wheel, said pawl being adapted to be moved from its position over the platen shaft, and a spring for holding said pawl in its normal and abnormal positions, substantially as set forth.

45 18. In a typewriting machine, the combination of a carriage, a platen supported thereon, a toothed wheel secured to one end of the platen, a line space lever, a pawl lever arranged between the end of the platen and the adjacent end of the carriage and connected to said line space lever, a pawl on said pawl lever for actuating said toothed wheel, said pawl lever and its connection with the line space lever being arranged within the

space bounded by the projecting edge of a sheet passing around the platen, a brake for the platen, and a brake lever which extends rearwardly relative to the platen, substantially as set forth.

19. In a typewriting machine, the combination of a carriage, a platen journaled thereon, a plate secured to the platen, and a friction brake arranged to act at the center of said plate, substantially as set forth.

20. In a typewriting machine, the combination of a carriage, a platen journaled thereon, an annular friction brake arranged substantially concentric with the platen at one end thereof, and an operating lever for moving said brake to an eccentric position to bear against the platen, substantially as set forth.

21. In a typewriting machine, the combination of a carriage, a platen journaled thereon, a plate secured to one end of the platen and provided with a conical opening, a conical friction brake arranged in said opening, and means for actuating said brake, substantially as set forth.

22. In a typewriting machine, the combination of a carriage, a platen journaled thereon, a plate secured to one end of the platen and provided with a conical opening, a conical friction brake arranged in said opening, and a spring for forcing the brake against the conical edge of said opening, substantially as set forth.

23. In a typewriting machine, the combination of a carriage, a platen journaled thereon, a toothed wheel secured to said platen, means for actuating said toothed wheel to turn the platen, a detent held by spring pressure against said toothed wheel, a brake for the platen, and an arm rigid with said brake for operating the same and arranged to directly engage said detent to hold the same out of engagement with said toothed wheel, the brake being applied by the pressure of said detent on said arm, substantially as set forth.

Witness my hand, this 4th day of April, 1906.

OSCAR C. KAVLE.
